(57) **CLAIM**

The ornamental design for a snap fastener, as shown and described.

DESCRIPTION

FIG. 1 is a front elevational view of a first component of a snap fastener shown separately for ease of illustration;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front perspective view thereof;

FIG. 8 is a rear perspective view thereof;

FIG. 9 is a front elevational view of a second component of the snap fastener shown separately for ease of illustration;

FIG. 10 is a rear elevational view of FIG. 9;

FIG. 11 is a left side view of FIG. 9;

FIG. 12 is a right side view of FIG. 9;

FIG. 13 is a top plan view of FIG. 9;

FIG. 14 is a bottom plan view of FIG. 9;

FIG. 15 is a rear perspective view of FIG. 9;

FIG. 16 is a front perspective view of FIG. 9;

FIG. 17 is a perspective view of the snap fastener with the first and the second components combined together, the perspective being of the front of the second component; and,

FIG. 18 is a perspective view of FIG. 17, the perspective being of the front of the first component.

The broken lines in the drawings illustrate portions of the snap fastener which form no part of the claimed design.

1 Claim, 14 Drawing Sheets
